[57] CLAIM

The ornamental design for putter face design nubbins, as shown and described.

DESCRIPTION

FIG. 1 is a front elevational view of a golf putter face showing a first embodiment of our new design;

FIG. 2 is perspective view of the putter face design of the first embodiment;

FIG. 3 is a sectional view of FIG. 2 along line III—III; and, FIG. 4 is a bottom plan view of the putter face design of the first embodiment.

The broken line showing of the golf club head is for illustrative purposes only and forms no part of the claimed design.
